(57) **ABSTRACT**

A head unit includes a recording head, a head-side frame, a unit frame, a first head mounting member, a second head mounting member, a head angle adjustment mechanism, and an urging member. The unit frame is configured to hold the recording head on both side surfaces of a main frame standing along a width direction orthogonal to a conveyance direction of a recording medium. The urging member is arranged on a side opposite to an opposing surface of the first head mounting member and the second head mounting member with respect to the main frame, and is configured to urge the head-side frame in a direction of separating away from the main frame. A counteraction of a pressing force that acts on the head-side frame from the urging member acts on the first head mounting member and the second head mounting member from the head-side frame.

HEAD UNIT AND INKJET RECORDING APPARATUS INCLUDING THE SAME

INCORPORATION BY REFERENCE

This application is based on and claims the benefit of priority from Japanese Patent Application No, 2021-68155 filed on Apr. 14, 2021, the contents of which are hereby incorporated by reference.

BACKGROUND

The present disclosure relates to a head unit to be mounted to an inkjet recording apparatus and an inkjet recording apparatus including the same, and more particularly, to a mounting structure for mounting a recording head to a head unit.

A head unit to be mounted to an inkjet recording apparatus includes a recording head including a plurality of nozzles configured to eject ink onto a recording medium, for example, a sheet, and is configured to record an image on a recording medium. In a so-called line head printer with recording heads arranged such that inkjet ejection nozzles are arranged along an entire region of a recording medium in a width direction, a head unit including a plurality of recording heads forming a unit for each color is used.

SUMMARY

A head unit according to one aspect of the present disclosure includes a recording head, a head-side frame, a unit frame, a first head mounting member, a second head mounting member, a head angle adjustment mechanism, and an urging member. The recording head includes a plurality of nozzles configured to eject ink onto a recording medium. The head-side frame is mounted to the recording head. The unit frame is configured to hold one or more recording heads on both side surfaces of a main frame having a flat-plate shape and standing along a width direction orthogonal to a conveyance direction of a recording medium. The first head mounting member is fixed to the main frame, and includes a support shaft configured to swingably support one end portion of the head-side frame in the width direction. The second head mounting member is fixed to the main frame, and is configured to support another end portion of the head-side frame in the width direction. The head angle adjustment mechanism is configured to adjust an angle of the recording head in a horizontal direction with respect to the unit frame by changing a position of the head-side frame in the horizontal direction with respect to the second head mounting member. The urging member is arranged on a side opposite to an opposing surface of the first head mounting member and the second head mounting member with respect to the main frame, and is configured to urge the head-side frame in a direction of separating away from the main frame. A counteraction of a pressing force that acts on the head-side frame from the urging member acts on the first head mounting member and the second head mounting member from the head-side frame.

BRIEF DESCRIPTION OF THE DRAWINGS

FIG. 1 is an explanatory view for illustrating a schematic configuration of a printer, which is an inkjet recording apparatus according to one embodiment of the present disclosure.

FIG. 2 is a plan view of a recording portion included in the printer.

FIG. 3 is a side view of a recording head forming a line head of the recording portion.

5 FIG. 4 is a plan view of the recording head as seen from an ink ejection face side.

FIG. 5 is a plan sectional view of the head unit as seen from above,

10 FIG. 6 is a perspective view of a unit frame forming the head unit.

FIG. 7 is a perspective view of a main frame forming the unit frame.

FIG. 8 is a perspective view of a first reinforcing member firming the unit frame.

15 FIG. 9 is a perspective view of a second reinforcing member forming the unit frame.

FIG. 10 is a perspective view for illustrating a state in which the first reinforcing member is mounted to a bent portion on a pivot fulcrum side of the main frame.

20 FIG. 11 is a perspective view for illustrating a state in which the first reinforcing member is mounted to a bent portion on a pivot end side of the main frame.

FIG. 12 is a plan view of a configuration of an engagement portion between the pivot fulcrum side of the unit frame and a main body frame of the printer as seen front above,

25 FIG. 13 is a perspective view for illustrating a configuration of a unit angle adjustment portion provided on the pivot end side of the unit frame.

30 FIG. 14 is a perspective view of a head-side frame to be mounted to the recording head.

FIG. 15 is a partial enlarged view of an end portion of the head-side frame on the pivot fulcrum side as seen from below.

35 FIG. 16 is a perspective view of the first head mounting member to be arranged on the pivot fulcrum side of the head-side frame.

FIG. 17 is a perspective view for illustrating a configuration of a coupling portion between the pivot fulcrum side of the head-side frame and the unit frame.

40 FIG. 18 is a side sectional view of the coupling portion between the pivot fulcrum side of the head-side frame and the unit frame taken along a direction orthogonal to a longitudinal direction.

45 FIG. 19 is a perspective view of a second head mounting member to be arranged on the pivot end side of the head-side frame.

FIG. 20 is a perspective view for illustrating a state in which a flat spring is mounted to the second head mounting member to be arranged on the pivot end side of the head-side frame.

50 FIG. 21 is a perspective view for illustrating a configuration of a coupling portion between the pivot end side of the head-side frame and the unit frame.

55 FIG. 22 is a side sectional view of the coupling portion between the pivot end side of the head-side frame and the unit frame taken along the direction orthogonal to the longitudinal direction, and is a sectional view including a head angle adjustment mechanism.

60 FIG. 23 is a side sectional view of the coupling portion between the pivot end side of the head-side frame and the unit frame taken along the direction orthogonal to the longitudinal direction, and is a sectional view including a flat spring.

65 FIG. 24 is a side sectional view of the coupling portion between the pivot end side of the head-side frame and the unit frame taken along the longitudinal direction.

FIG. 25 is a perspective view for illustrating a state of coupling between the pivot end side of the head-side frame and the second head mounting member.

FIG. 26 is a perspective view for illustrating a state in which a sliding plate is mounted to a sliding portion of the second head mounting member.

DETAILED DESCRIPTION

Now, an embodiment of the present disclosure is described with reference to the drawings. FIG. 1 is an explanatory view for illustrating a schematic configuration of a printer 100, which is an inkjet recording apparatus according to one embodiment of the present disclosure. The printer 100 includes a sheet feeding cassette 2, which is a sheet accommodating portion. The sheet feeding cassette 2 is arranged on a lower side inside a printer main body 1. The sheet feeding cassette 2 accommodates sheets P, which are an example of recording media.

A sheet feeding device 3 is arranged on a downstream side of the sheet feeding cassette 2 in a sheet conveyance direction, that is, on an upper right side of the sheet feeding cassette 2 in FIG. 1. With this sheet feeding device 3, the sheets P are separated and sent out one after another toward the upper right side of the sheet feeding cassette 2 in FIG. 1.

The printer 100 includes a first sheet conveyance passage 4a inside thereof. The first sheet conveyance passage 4a is located on the upper right side with respect to the sheet feeding cassette 2, which corresponds to a sheet-feeding direction of the sheet feeding cassette 2. The sheet P having been sent out from the sheet feeding cassette 2 is conveyed by the first sheet conveyance passage 4a vertically upward along a side surface of the printer main body 1.

A registration roller pair 13 is provided at a downstream end of the first sheet conveyance passage 4a in the sheet conveyance direction. Further, a first conveyance unit 5 and a recording portion 9 are arranged in proximity to a downstream side of the registration roller pair 13 in the sheet conveyance direction. The sheet P having been sent out from the sheet feeding cassette 2 passes through the first sheet conveyance passage 4a to reach the registration roller pair 13. The registration roller pair 13 sends out the sheet P toward the first conveyance unit 5 (in particular, first conveyance belt 8 described later) at the timing matching the timing of an ink ejection operation performed by the recording portion 9, while correcting skew feed of the sheet P.

The sheet P having been sent out to the first conveyance unit 5 by the registration roller pair 13 is conveyed by the first conveyance belt 8 to a position opposing the recording portion 9 (in particular, recording heads 17a to 17c described later). Through ejection of ink from the recording portion 9 onto the sheet P, an image is recorded on the sheet P. In this case, the ejection of the ink in the recording portion 9 is controlled by a controller 120 provided inside the printer 100.

A second conveyance unit 12 is arranged on a downstream side of the first conveyance unit 5 in the sheet conveyance direction (left side in FIG. 1). The sheet P having the image recorded thereon by the recording portion 9 is sent to the second conveyance unit 12. The ink having been ejected onto a surface of the sheet P is dried while passing through the second conveyance unit 12.

A decurler portion 14 is provided in the vicinity of a left side surface of the printer main body 1 on a downstream side of the second conveyance unit 12 in the sheet conveyance direction. The sheet P having the ink dried by the second

conveyance unit 12 is sent to the decurler portion 14, and the curl in the sheet P is corrected.

A second sheet conveyance passage 4b is provided on a downstream side of the decurler portion 14 in the sheet conveyance direction (upper side in FIG. 1). When duplex recording is not to be performed, the sheet P having passed through the decurler portion 14 passes through the second sheet conveyance passage 4b and then is discharged to a sheet discharge tray 15a provided outside the left side surface of the printer 100. A sub discharge tray 15b configured to discharge an unnecessary sheet P suffered from, for example, poor printing (waste sheet) is provided below the sheet discharge tray 15a.

A turn-over conveyance passage 16 for the duplex recording is provided at an upper portion of the printer main body 1 above the recording portion 9 and the second conveyance unit 12. When the duplex recording is to be performed, the sheet P having been subjected to the recording on one surface (first surface) of the sheet P and having passed through the second conveyance unit 12 and the decurler portion 14 is sent to the turn-over conveyance passage 16 through the second sheet conveyance passage 4b.

A conveyance direction of the sheet P having been sent to the turn-over conveyance passage 16 is then switched for recording on another surface (second surface) of the sheet P. Then, the sheet P passes through the upper portion of the printer main body 1 to be sent to the right side, and is sent again to the first conveyance unit 5 via the registration roller pair 13 under a state in which the second surface of the sheet P faces upward. In the first conveyance unit 5, the sheet P is conveyed to the position opposing the recording portion 9. Through ejection of ink from the recording portion 9, an image is recorded on the second surface. The sheet P having been subjected to the duplex recording passes through the second conveyance unit 12, the decurler portion 14, and the second sheet conveyance passage 4b in the stated order to be discharged to the sheet discharge tray 15a.

Further, a maintenance unit 19 and a cap unit 20 are arranged below the second conveyance unit 12. At the time of performing purging, the maintenance unit 19 horizontally moves to a position below the recording portion 9 to wipe ink having been pushed out from ink ejection ports of the recording heads and collects the ink having been wiped. The "purging" refers to an operation of forcibly pushing out the ink from the ink ejection ports of the recording heads in order to discharge thickened ink, foreign matters, and air bubbles inside the ink ejection ports. At the time of capping ink ejection faces of the recording heads, the cap unit 20 horizontally moves to a position below the recording portion 9 and further moves upward to be mounted to the lower surfaces of the recording heads.

FIG. 2 is a plan view of the recording portion 9. The recording portion 9 includes a head housing 10 and line heads 11Y, 11M, 11C, and 11K. The line heads 11Y to 11K are held by the head housing 10 at such a height that a predetermined distance (for example, 1 mm) is defined with respect to a conveyance surface of the first conveyance belt 8 having an endless shape, which extends in a tensioned state around a plurality of rollers including a driving roller 6a, a driven roller 6b, and a tension roller (not shown). The driving roller 6a allows the first conveyance belt 8 to run in the conveyance direction of the sheet P (arrow A direction).

The line heads 11Y to 11K each include a plurality of (three in this embodiment) recording heads 17a to 17c. The recording heads 17a to 17c are arrayed in a staggered pattern along a sheet width direction (arrow BB' direction) orthogonal to the sheet conveyance direction (arrow A direction).

The recording heads 17a to 17c each include a plurality of ink ejection ports 18 (nozzles). The ink ejection ports 18 are arranged side by side at equal intervals in the width direction of the recording head, that is, in the sheet width direction (arrow BB' direction). Inks of respective colors including yellow (Y), magenta (M), cyan (C), and black (K) are ejected from the line heads 11Y to 11K through the ink ejection ports 18 of the recording heads 17a to 17c toward the sheet P conveyed on the first conveyance belt 8.

FIG. 3 is a side view of the recording heads 17a to 17c forming the line heads 11Y to 11K of the recording portion 9. FIG. 4 is a plan view of the recording heads 17a to 17c as seen from an ink ejection face SF1 side. The recording heads 17a to 17c have the same shape and configuration. Thus, in FIG. 3 and FIG. 4, the recording heads 17a to 17c are illustrated in one drawing. As illustrated in FIG. 3 and FIG. 4, the ink ejection face (nozzle face) SF1 of the recording heads 17a to 17c has a plurality of (four blocks in this embodiment) nozzle regions Ra to Rd each having a large number of ink ejection ports 18 (see FIG. 2) arrayed therein. The ink ejection face SF1 is made of, for example, SUS (stainless steel).

The recording heads 17a to 17c forming the line heads 11Y to 11K receive supply of inks of four colors (yellow, magenta, cyan, and black), which are respectively designated for the line heads 11Y to 11K, from a liquid supply mechanism (not shown).

In response to a control signal from the controller 120 (see FIG. 1), and in accordance with image data received from an external computer, the recording heads 17a to 17c eject the ink, from the ink ejection ports 18 toward the sheet P being conveyed in a state of being attracted to and held on the conveyance surface of the first conveyance belt 8. With this operation, a color image which is formed by superimposing the ink images of four colors including yellow, magenta, cyan, and black is formed on the sheet P on the first conveyance belt 8. Further, a cleaning liquid supply portion 30 configured to supply a cleaning liquid is provided at one end portion of the recording heads 17a to 17c in a longitudinal direction (arrow BB' direction) orthogonal to the sheet conveyance direction (arrow A direction). The cleaning liquid supply portion 30 has a large number of cleaning liquid supply ports 30a.

In the printer 100, in order to clean the ink ejection faces SF1 of the recording heads 17a to 17c, at the time of starting printing after a long period of suspension and during breaks of printing operations, a recovery operation for the recording heads 17a to 17c, specifically, an operation of pushing out (purging) the ink from the ink ejection ports 18 of all the recording heads 17a to 17c and then supplying the cleaning liquid from the cleaning liquid supply ports 30a to cleaning liquid supply faces SF2 and wiping off the ink ejected to the ink ejection face SF1 together with the cleaning liquid with a wiper (not shown) is performed, to thereby prepare for the next printing operation. The ink and the cleaning liquid having been wiped off from the ink ejection face SF1 is collected by an ink receiving portion (not shown).

Next, a configuration of a head unit 51 of the printer 100 is described, FIG. 5 is a plan sectional view of the head unit 51 as seen from above. FIG. 6 is a perspective view of a unit frame 52 forming the head unit 51. FIG. 7 is a perspective view of a main frame 53 forming the unit frame 52. The head unit 51 includes the recording heads 17a to 17c and the unit frame 52. The unit frame 52 is configured to hold the recording heads 17a to 17c such that the recording heads 17a to 17c are individually removable.

The recording heads 17a to 17c are arrayed in a staggered pattern on both side surfaces of the unit frame 52 along the sheet width direction (arrow BB' direction). More specifically, the recording heads 17a and 17c are held on an upstream side of the unit frame 52 in the sheet conveyance direction (arrow A direction), and the recording head 17b is held on a downstream side.

The unit frame 52 includes the main frame 53, first reinforcing members 55, and a second reinforcing member 57. As illustrated in FIG. 7, the main frame 53 includes a main body portion 53a and bent portions 53b. The main body portion 53a having a flat-plate shape extends in an up-and-down direction and in the sheet width direction and is opposed to side surfaces of the recording heads 17a to 17c. The bent portions 53b are formed by perpendicularly bending both end portions of the main body portion 53a in the sheet width direction. First head mounting members 80a and second head mounting members 80b which are configured to hold the recording heads 17a to 17c are fixed to the main body portion 53a at predetermined locations. The first head mounting members 80a and the second head mounting members 80b are each an aluminum block member formed by aluminum die-casting.

The first head mounting members 80a each include a support shaft boss 81 (see FIG. 16) configured to support one end portion of the recording heads 17a to 17c in the longitudinal direction (end portion in the arrow B' direction) such that the recording heads 17a to 17c are rotatable in the horizontal direction. The support structure for supporting the recording heads 17a to 17c with the first head mounting member 80a is described later.

The second head mounting members 80b are each configured to support another end portion of the recording heads 17a to 17c in the longitudinal direction (end portion in the arrow B direction). Head angle adjustment mechanisms 60 are each configured to perform angle adjustment (alignment adjustment) of the recording heads 17a to 17c in the horizontal direction with respect to the unit frame 52 by moving the end portion of the recording heads 17a to 17c (end portion in the arrow B direction) in an Ra direction or an Rb direction with respect to the unit frame 52. A specific configuration of the head angle adjustment mechanism 60 is described later.

Further, one end portion of the head unit 51 in the longitudinal direction (end portion in the arrow B' direction) is support so as to be pivotable in the horizontal direction with respect to a main body frame 101 (see FIG. 12) of the printer 100. A unit angle adjustment mechanism 110 (see FIG. 13) configured to perform angle adjustment of the head unit 51 with respect to the main body frame 101 is arranged at another end portion of the head unit 51 in the longitudinal direction (end portion in the arrow B direction).

FIG. 8 and FIG. 9 are perspective views of the first reinforcing member 55 and the second reinforcing member 57 each forming the unit frame 52. The first reinforcing member 55 is formed by bending a metal plate into a predetermined shape, and includes a side wall portion 55a, a bottom surface portion 55b, a first coupling piece 55c, and a second coupling piece 55d.

The side wall portion 55a is fixed to the main body portion 53a of the main frame 53. The bottom surface portion 55b is provided so as to extend in the horizontal direction from a lower end portion of the side wall portion 55a toward one side (front side in FIG. 8), and includes first engagement protrusions 56a and 56b, a second engagement protrusion 56c, and a unit positioning hole 59. The first engagement protrusions 56a and 56b project from side end

edges on one side (left side in FIG. 8) and another side (right side in FIG. 8) of the bottom surface portion 55b, respectively, and the second engagement protrusion 56c projects from the lower end portion of the side wall portion 55a through an opening portion 55e toward a side opposite to the bottom surface portion 55b (back side in FIG. 8). The unit positioning hole 59 engages with a support shaft 102 (see FIG. 12) of the main body frame 101 when the first reinforcing member 55 is mounted on a fulcrum side (left side in FIG. 6) of the unit frame 52.

The first coupling piece 55c and the second coupling piece 55d are provided so as to extend in the horizontal direction from an upper end portion of the side wall portion 55a toward one side (front side in FIG. 8) and another side (back side in FIG. 8), respectively. The first coupling piece 55c and the second coupling piece 55d each have a screw hole 58a for fixing by screw a flow passage structure (not shown), which is configured to supply liquid such as ink or a cleaning liquid to the recording heads 17a to 17c, to the unit frame 52. A ridge portion defined between the side wall portion 55a and the second coupling piece 55d has a first engagement hole 55f to be engaged with a positioning protrusion 53c (see FIG. 7) formed at an upper end portion of the main frame 53.

The second reinforcing member 57 is formed by bending a metal plate into a predetermined shape, and includes a support portion 57a and an upper surface portion 57b. The support portion 57a is fixed to the main body portion 53a of the main frame 53. The support portion 57a has a screw hole 58b for fixing to the main body portion 53a. The upper surface portion 57b is provided so as to extend in the horizontal direction from an upper end portion of the support portion 57a, and has a screw hole 58a for fixing by screw the flow passage structure (not shown) to the unit frame 52. A ridge portion defined between the support portion 57a and the upper surface portion 57b has a second engagement hole 57c to be engaged with a positioning protrusion 53d (see FIG. 7) formed at an upper end portion of the main frame 53.

FIG. 10 and FIG. 11 are perspective views for illustrating a state in which the first reinforcing members 55 are mounted to the bent portions 53b on the pivot fulcrum side (left side in FIG. 6) and the pivot end side (right side in FIG. 6) of the main frame 53, respectively. As illustrated in FIG. 10, on the pivot fulcrum side of the main frame 53, the first reinforcing member 55 is positioned with respect to the main frame 53 by engaging the first engagement hole 55f of the first reinforcing member 55 with the positioning protrusion 53c.

In this manner, the side end edge of the side wall portion 55a of the first reinforcing member 55 on one side (left side in FIG. 8) is arranged along a ridge line L1 being a bend portion defined between the main body portion 53a and the bent portion 53b. Further, the side end edge of the bottom surface portion 55b on one side (left side in FIG. 8) is arranged along an inner side surface of the bent portion 53b. Then, the first engagement protrusion 56a, of the first reinforcing member 55 is engaged with the engagement hole 53e formed in the bent portion 53b, and the second engagement protrusion 56c is engaged with the engagement hole 53e (see FIG. 7) formed in the main body portion 53a, respectively. In this state, the side wall portion 55a is fixed by screw to the main body portion 53a so that mounting of the first reinforcing member 55 is completed.

As illustrated in FIG. 11, on the pivot end side of the main frame 53, the first reinforcing member 55 is positioned with respect to the main frame 53 by engaging the first engagement hole 55f of the first reinforcing member 55 with the

positioning protrusion 53c. In this manner, the side end edge of the side wall portion 55a of the first reinforcing member 55 on another side (right side in FIG. 8) is arranged along the ridge line L1 being a bend portion defined between the main body portion 53a and the bent portion 53b. Further, the side end edge of the bottom surface portion 55b on another side (right side in FIG. 8) is arranged along an inner side surface of the bent portion 53b. Then, the first engagement protrusion 56a of the first reinforcing member 55 is engaged with the engagement hole 53e formed in the bent portion 53b, and the second engagement protrusion 56c is engaged with the engagement hole 53e (see FIG. 7) formed in the main body portion 53a, respectively. In this state, the side wall portion 55a is fixed by screw to the main body portion 53a so that mounting of the first reinforcing member 55 is completed.

In this embodiment, the first reinforcing member 55 is assembled to the main frame 53 such that the ridge line L1 being the bend portion defined between the main body portion 53a and the bent portion 53b of the main frame 53 and a ridge line L2 being a bend portion defined between the side wall portion 55a and the bottom surface portion 55b of the first reinforcing member 55 are orthogonal to each other. Further, the first engagement protrusions 56a and 56b and the second engagement protrusion 56c formed on the bottom surface portion 55b of the first reinforcing member 55 are inserted into the engagement holes 53e of the main frame 53. In this manner, the rigidity of the both end portions of the assembled unit frame 52 in the up-and-down direction and in the width direction can be improved.

Further, the first reinforcing members 55 having the same shape are mounted on the pivot fulcrum side and the pivot end side of the main frame 53, respectively. Thus, erroneous mounting can be prevented as compared to a case in which different members are mounted, thereby improving the ease of operation of mounting. Further, the number of members can be reduced, thereby facilitating management of members.

FIG. 12 is a plan view of a configuration of an engagement portion between the pivot fulcrum side (left side in FIG. 6) of the unit frame 52 and the main body frame 101 of the printer 100 as seen from above. As illustrated in FIG. 12, on the pivot fulcrum side of the unit frame 52, the unit positioning hole 59 of the first reinforcing member 55 is engaged with the support shaft 102 of the main body frame 101. Further, on the main body frame 101, a pressing member 103 is arranged adjacent to the unit frame 52. The pressing member 103 is urged by two coil springs 104 in a direction of approaching the unit frame 52.

With this configuration, the unit frame 52 is pressed by the pressing member 103 toward the pivot end side (arrow B direction) so that two sides of the unit positioning hole 59 having a pentagonal shape (home-base shape) adjacent to each other over an apex is brought into press-contact with the support shaft 102. Thus, positioning of the unit frame 52 in the longitudinal direction (arrow BB' direction) can be performed easily and reliably.

FIG. 13 is a perspective view for illustrating a configuration of the unit angle adjustment mechanism 110 provided on the pivot end side of the unit frame 52. The unit angle adjustment mechanism 110 is arranged close to the side surface of the unit frame 52 on the pivot end side, and includes an angle adjustment member 111, a compression spring 112, and an operation member 113. Further, the unit frame 52 is urged by an urging mechanism (not shown) in the Ra direction about the support shaft 102 (see FIG. 12).

The angle adjustment member 111 is a rod-shaped member extending in the horizontal direction, and includes an

adjustment rotation shaft 111a and a head contact portion 111b. The compression spring 112 urges the angle adjustment member 111 in a clockwise direction about the adjustment rotation shaft 111a. The operation member 113 is rotatable supported on the main body frame 101. Rotation of the operation member 113 in a forward direction or a reverse direction causes the operation member 113 to move in a direction of coming into contact with or separating away from one end portion of the angle adjustment member 111.

When the operation member 113 is forwardly rotated so as to move in the direction of coming closer to the angle adjustment member 111, one end portion of the angle adjustment member 111 is pressed so that the angle adjustment member 111 rotates in a counterclockwise direction against an urging force of the compression spring 112. As a result, the unit frame 52 is pressed by the head contact portion 111b and rotates in the Rb direction against an urging force of the urging mechanism. Meanwhile, when the operation member 113 is reversely rotated so as to move in the direction of separating away from the angle adjustment member 111, the angle adjustment member 111 rotates in the clockwise direction by the urging force of the compression spring 112. As a result, the head contact portion 111b moves in the direction of separating away from the unit frame 52 so that the unit frame 52 rotates in the Ra direction by the urging force of the urging mechanism.

FIG. 14 is a perspective view of a head-side frame 70 to be mounted to the recording heads 17a to 17c. The head-side frame 70 is formed by bending a metal plate into a U-shape in sectional view, and includes a flat portion 70a and side-surface portions 70b and 70c. The flat portion 70a extends in the sheet width direction (arrow BB' direction). The side-surface portions 70b and 70c stand upright from side end edges of the flat portion 70a in the longitudinal direction. The head-side frame 70 is supported so as to be pivotable in the horizontal direction, with one side (left far side in FIG. 14) in the longitudinal direction with respect to the unit frame 52 serving as a pivot fulcrum and another side (right near side in FIG. 14) serving as a pivot end. On the pivot end side of the side-surface portion 70c, a first angle adjustment screw 61 for adjusting an angle of the head-side frame 70 in the horizontal direction (Ra and Rb directions) with respect to the unit frame 52 is threadedly inserted.

FIG. 15 is a partial enlarged view of the pivot fulcrum side of the head-side frame 70 as seen from below. As illustrated in FIG. 15, a head positioning hole 71 and adjustment screw mounting holes 72 are formed at an end portion of the flat portion 70a on the pivot fulcrum side. The head positioning hole 71 has a hexagonal shape. The adjustment screw mounting holes 72 receive height adjustment screws 75a and 75b, which are described later, to be threadedly inserted thereinto.

FIG. 16 is a perspective view of the first head mounting member 80a to be arranged on the pivot fulcrum side of the head-side frame 70. The first head mounting member 80a has the support shaft boss 81 and screw holes 83a to 83c. The support shaft boss 81 is inserted into the head positioning hole 71 of the head-side frame 70 to serve as a pivot fulcrum of the head-side frame 70. A screw 77a for fixing a flat spring 76 (refer to FIG. 18 for both) to the first head mounting member 80a is fastened to the screw hole 83a. A screw (not shown) for fixing the first head mounting member 80a to the main frame 53 is fastened to the screw hole 83b (see FIG. 18). The screw hole 83c is formed along an axial center of the support shaft boss 81, and a head fixing pin 73 (see FIG. 18) for fixing the recording heads 17a to 17c is fastened to the screw hole 83c.

FIG. 17 is a perspective view for illustrating a configuration of a coupling portion between the pivot fulcrum side of the head-side frame 70 and the unit frame 52, FIG. 18 is a side sectional view of the coupling portion between the pivot fulcrum side of the head-side frame 70 and the unit frame 52 taken along a direction orthogonal to the longitudinal direction. As illustrated in FIG. 17 and FIG. 18, the support shaft boss 81 of the first head mounting member 80a is inserted from above the head positioning hole 71 of the head-side frame 70. Further, the head fixing pin 73 is fastened through the head positioning hole 71 from below the head-side frame 70. A head fixing spring 74 is sandwiched between the head fixing pin 73 and the head-side frame 70. In this manner, the head-side frame 70 is held in press-contact with the first head mounting member 80a by an urging force of the head fixing spring 74.

Further, the height adjustment screws 75a and 75b are threadedly inserted into the adjustment screw mounting holes 72 of the head-side frame 70 from below. When the height adjustment screws 75a and 75b are rotated in a forward direction (clockwise direction), the height adjustment screws 75a and 75b project upward to push up a lower surface of the first head mounting member 80a. As a result, the head-side frame 70 moves downward against the urging force of the head fixing spring 74. When the height adjustment screws 75a and 75b are rotated in a reverse direction (counterclockwise direction), the height adjustment screws 75a and 75b retreat downward so that the head-side frame 70 moves upward by the urging force of the head fixing spring 74.

Further, the flat spring 76 (urging member) is mounted on a side surface (right side surface in FIG. 18) of the first head mounting member 80a on a side opposite to an opposing surface with respect to the main frame 53. An upper end portion of the flat spring 76 is fixed with the screw 77a to the first head mounting member 80a, and a lower end portion of the flat spring 76 abuts against an inner side surface of the side-surface portion 70b of the head-side frame 70. In this manner, the head-side frame 70 is urged in a direction of separating away from the main frame 53 by the urging force of the flat spring 76, thereby being capable of maintaining a fixed positional relationship between the unit frame 52 and the head-side frame 70 in the conveyance direction (arrow A direction).

In this case, a pressing force F1 acts on the head-side frame 70 from the flat spring 76 so that a force F1' acts on the first head mounting member 80a from the flat spring 76 as a counteraction of the pressing force F1. That is, a force relationship of the action and the counteraction is completed between the first head mounting member 80a and the head-side frame 70, and a force applied by the flat spring 76 does not directly act on the main frame 53. Thus, deformation of the main frame 53 can be prevented.

FIG. 19 is a perspective view of the second head mounting member 80b to be arranged on the pivot end side of the head-side frame 70, FIG. 20 is a perspective view for illustrating a state in which the flat spring 76 is mounted to the second head mounting member 80b. The second head mounting member 80b has a sliding portion 82 and screw holes 83a to 83c. The sliding portion 82 is a portion having an L-shape in side view and integrally formed on a lower side of the second head mounting member 80b, and a second angle adjustment screw 62 is threadedly inserted into a vertical portion of the L-shape. The sliding portion 82 slides along the flat portion 70a at the time of performing angle adjustment of the head-side frame 70 with the first angle adjustment screw 61 (see FIG. 14) and the second angle

11

adjustment screw 62. Engagement claws 82a for mounting a sliding plate 90 (see FIG. 25) are formed at both end portions of the sliding portion 82 in the longitudinal direction.

The screw 77a for fixing the flat spring 76 to the second head mounting member 80b is fastened to the screw hole 83a (see FIG. 23). The screw 77b (see FIG. 23) for fixing the second head mounting member 80b to the main frame 53 is fastened to the screw hole 83b. The screw hole 83c is formed at a center of a lower surface of the sliding portion 82, and the head fixing pin 73 (see FIG. 23) for fixing the recording heads 17a to 17c is fastened to the screw hole 83c.

FIG. 21 is a perspective view for illustrating a configuration of a coupling portion between the pivot end side of the head-side frame 70 and the unit frame 52. FIG. 22 and FIG. 23 are each a side sectional view of the coupling portion between the pivot end side of the head-side frame 70 and the unit frame 52 taken along the direction orthogonal to the longitudinal direction. FIG. 22 and FIG. 23 are sectional views including the head angle adjustment mechanism 60 and the flat spring 76, respectively. FIG. 24 is a side sectional view of the coupling portion between the pivot end side of the head-side frame 70 and the unit frame 52 taken along the longitudinal direction.

As illustrated in FIG. 21 to 24, the head fixing pin 73 is fastened to the screw hole 83c of the second head mounting member 80b through an elongated head positioning hole 78 formed in the head-side frame 70. The head fixing spring 74 is sandwiched between the head fixing pin 73 and the head-side frame 70. In this manner, the head-side frame 70 is held in press-contact with the second head mounting member 80b by an urging force of the head fixing spring 74.

Further, a height adjustment screw 75c is threadedly inserted into the head-side frame 70 from below. When the height adjustment screw 75c is rotated in a forward direction (clockwise direction), the height adjustment screw 75c projects upward to push up a lower surface of the second head mounting member 80b. As a result, the head-side frame 70 moves downward against the urging force of the head fixing spring 74. When the height adjustment screw 75c is rotated in a reverse direction (counterclockwise direction), the height adjustment screw 75c retreats downward so that the head-side frame 70 moves upward by the urging force of the head fixing spring 74.

Through individual adjustment of the height adjustment screws 75a and 75b (see FIG. 18) on the pivot fulcrum side of the head-side frame 70 and the height adjustment screw 75c, a height and an angle of the recording heads 17a to 17c in a vertical direction can be adjusted. Two height adjustment screws 75a and 75h are provided on the pivot fulcrum side of the head-side frame 70, whereas only the height adjustment screw 75c is provided on the pivot end side of the head-side frame 70. This is because the flat portion 70a of the head-side frame 70 is positioned on a plane including distal ends of the height adjustment screws 75a to 75c (three points) by bringing the flat portion 70a into abutment against the distal ends of the height adjustment screws 75a to 75c.

Further, the head angle adjustment mechanism 60 is provided between the head-side frame 70 and the second head mounting member 80b. The head angle adjustment mechanism 60 includes the first angle adjustment screw 61 and the second angle adjustment screw 62. The first angle adjustment screw 61 is provided on an opposing surface of the side-surface portion 70c of the head-side frame 70 with respect to the sliding portion 82 of the second head mounting member 80b. The first angle adjustment: screw 61 passes through the side-surface portion 70c in the vertical direction,

12

and is reciprocally movable along the conveyance direction (arrow A direction) orthogonal to the support shaft boss 81. The first angle adjustment screw 61 is formed of, for example, a setscrew having a hexagonal hole or a slot at an end portion.

The second angle adjustment screw 62 is provided on an opposing surface of the sliding portion 82 of the second head mounting member 80b with respect to the side-surface portion 70c of the head-side frame 70. The second angle adjustment screw 62 passes through the sliding portion 82 in the vertical direction, and is reciprocally movable along the conveyance direction (arrow A direction) orthogonal to the support shaft boss 81. The second angle adjustment screw 62 is formed of, for example, a setscrew having a hexagonal hole or a slot at an end portion.

The first angle adjustment screw 61 and the second angle adjustment screw 62 are arranged at positions opposing each other in the conveyance direction (arrow A direction) orthogonal to the support shaft boss 81. More specifically, the first angle adjustment screw 61 and the second angle adjustment screw 62 are arranged at positions opposing each other in the longitudinal direction (sheet width direction, arrow BB' direction) and in the up-and-down direction of the head unit 51, and the first angle adjustment screw 61 and the second angle adjustment screw 62 reciprocally move on the same axis.

According to the configuration described above, at the time of assembly of the head unit 51 the second angle adjustment screws 62 of the second head mounting member 80b are adjusted in advance at predetermined positions. Then, after the first angle adjustment screws 61 of the recording heads 17a to 17c are adjusted to predetermined positions, the recording heads 17a to 17c are mounted to the unit frame 52. In this manner, in the case of replacing any one of the recording heads 17a to 17c, the operation of replacement can be completed by only removing the recording heads 17a to 17c for which replacement is required and thereafter mounting new recording heads 17a to 17c with the first angle adjustment screw 61 having been adjusted to the unit frame 52 with the second angle adjustment screw 62 having been adjusted. Thus, the alignment adjustment with respect to the unit frame 52 at the time of replacement of the recording heads 17a to 17c can easily be performed.

Further, the flat spring 76 is mounted on the side surface (right side surface in FIG. 23) of the second head mounting member 80b on the side opposite to the opposing surface with respect to the main frame 53. The upper end portion of the flat spring 76 is fixed by the screw 77a to the second head mounting member 80b, and the lower end portion of the flat spring 76 abuts against the inner side surface of the side-surface portion 70b of the head-side frame 70. In this manner, the head-side frame 70 is urged in the direction of separating away from the main frame 53 (direction of approaching the sliding portion 82) by the urging force of the flat spring 76, thereby being capable of maintaining a contact state between the first angle adjustment screw 61 and the second angle adjustment screw 62.

In this case, as illustrated in FIG. 23, the pressing force F1 acts on the head-side frame 70 from the flat spring 76 so that the force F1' acts on the second head mounting member 80b from the flat spring 76 as a counteraction of the pressing force F1. Further, a pressing force F2 acts on the first angle adjustment screw 61 (side-surface portion 70c) from the second angle adjustment screw 62 so that a force F2' acts on the second angle adjustment screw 62 (second head mounting member 80b) from the first angle adjustment screw 61 as a counteraction of the pressing force F2. That is, a force

13

relationship of the action and the counteraction is completed between the second head mounting member **80b** and the head-side frame **70**, and a force applied by the flat spring **76** does not directly act on the main frame **53**. Thus, deformation of the main frame **53** can be prevented.

FIG. 25 is a perspective view for illustrating a state of coupling between the pivot end side of the head-side frame **70** and the second head mounting member **80b**. FIG. 26 is a perspective view for illustrating a state in which the sliding plate **90** is mounted to the sliding portion **82** of the second head mounting member **80b**. As illustrated in FIG. 25, the head-side frame **70** is urged in the upward direction by the head fixing spring **74**, and a distal end of the height adjustment screw **75c** is held in press-contact with the lower surface of the sliding portion **82**.

When a sliding load between the height adjustment screw **75c** and the sliding portion **82** is large, the second head mounting member **80b** does not smoothly move at the time of alignment adjustment of the recording heads **17a** to **17c** by the head angle adjustment mechanism **60**, with the result that the alignment adjustment is hindered. In view of this, as illustrated in FIG. 25 and FIG. 26, the sliding plate **90** is mounted to the lower surface of the sliding portion **82** of the second head mounting member **80b**.

The sliding plate **90** is a sheet metal member made of, for example, SUS (stainless steel), and both end portions of the sliding plate **90** in the longitudinal direction are bent upward. A pair of engaged portions **90a** each formed of a rectangular opening are formed in the bend portions. The sliding plate **90** is mounted to the lower surface of the sliding portion **82** by engaging the engagement claws **82a** of the sliding portion **82** with the engaged portions **90a**. The sliding plate **90** is mounted to the second head mounting member **80b** with backlash (play) in the up-and-down direction, and has such structure that the sliding plate **90** comes into close contact with the lower surface of the sliding portion **82** by mounting the head fixing pin **73** and the head fixing spring **74**. The material of the sliding plate **90** is not limited to the SUS (stainless steel), and may be any material having a slidability and a rigidity greater than those of the second head mounting member **80b**.

With the sliding plate **90** provided to the sliding portion **82**, damage or dent on the second head mounting member **80b** caused by contact with the height adjustment screw **75c** can be prevented. Further, through the sliding of the height adjustment screw **75c** and the sliding plate **90** at the time of the alignment adjustment of the recording heads **17a** to **17c** with the head angle adjustment mechanism **60**, the sliding load between the height adjustment screw **75c** and the sliding portion **82** is reduced, thereby improving the followability of the second head mounting member **80b**. Thus, the alignment adjustment can be performed smoothly and accurately.

Further, the sliding plate **90** is mounted to the second head mounting member **80b** with backlash (play). Thus, the sliding plate **90** can easily be mounted to the second head mounting member **80b** regardless of the parts tolerance of the second head mounting member **80b** and the sliding plate **90**, thereby improving the ease of assembly operation. Further, with the engagement claws **82a** provided on the second head mounting member **80b** side and the engaged portions **90a** provided on the sliding plate **90** side, at the time of removing the head fixing pin **73** and the head fixing spring **74** and solely replacing one of the recording heads **17a** to **17c**, the sliding plate **90** is held without falling off the second head mounting member **80b**.

14

According to the configuration of this embodiment, the head unit **51** includes a plurality of (three in this embodiment) recording heads **17a** to **17c** arranged side by side on both sides of the unit frame **52**. According to this configuration, for example, when there is need for replacing one recording head **17a**, the other two recording heads **17b** and **17c** can continuously be used without replacement. Thus, reduction in cost of the head unit **51** can be achieved.

Further, the flat spring **76** for maintaining a fixed positional relationship between the unit frame **52** and the head-side frame **70** in the conveyance direction (arrow A direction) is mounted on the side surface of the first head mounting member **80a** and the second head mounting member **80b** on the side opposite to the main frame **53**. In this case, the pressing force **F1** acts on the head-side frame **70** from the flat spring **76**, and the force **F1'** acts on the first head mounting member **80a** or the second head mounting member **80b** from the flat spring **76** as a counteraction of the pressing force **F1**. Thus, the force relationship of the action and the counteraction is completed between the first head mounting member **80a** or the second head mounting member **80b** and the head-side frame **70**. As a result, the force applied by the flat spring **76** does not directly act on the main frame **53**, thereby being capable of preventing deformation of the main frame **53**.

Further, with the sliding plate **90** mounted to the sliding portion **82** of the second head mounting member **80b**, damage or dent on the second head mounting member **80b** caused by the height adjustment screw **75c** can be prevented. Further, through the sliding of the height adjustment screw **75c** and the sliding plate **90** at the time of the alignment adjustment of the recording heads **17a** to **17c**, the sliding load between the height adjustment screw **75c** and the sliding portion **82** is reduced, thereby being capable of performing the alignment adjustment smoothly and accurately.

Further, the printer **100** includes the head unit **51** having the configuration described above, which is configured to record an image on the sheet **S**. According to this configuration, in the printer **100**, only any of the recording heads **17a** to **17c** having failure can be replaced individually. Thus, the printer **100** has a configuration which is reduced in cost.

Besides, the present disclosure is not limited to the embodiment described above, and various modifications can be made within the scope not departing from the gist of the present disclosure. For example, in the embodiment described above, description has been given of the configuration in which three recording heads **17a** to **17c** are mounted to one head unit **51**. However, there may also be employed a configuration in which two or four or more recording heads are mounted to the head unit **51**.

The present disclosure is applicable to a head unit including a removable recording head or to an inkjet recording apparatus such as an inkjet printer including the head unit.

What is claimed is:

1. A head unit, comprising:
a recording head including a plurality of nozzles configured to eject ink onto a recording medium;
a head-side frame mounted to the recording head;
a unit frame configured to hold one or more recording heads on both side surfaces of a main frame having a flat-plate shape and standing vertically along a width direction orthogonal to a conveyance direction of the recording medium;
a first head mounting member which is fixed to a side surface of the main frame, and includes a support shaft

15

configured to swingably support one end portion of the head-side frame in the width direction; a second head mounting member which is fixed to the side surface of the main frame, and is configured to support another end portion of the head-side frame in the width direction; a head angle adjustment mechanism configured to adjust an angle of the recording head in a horizontal direction with respect to the unit frame by changing a position of the head-side frame in the horizontal direction with respect to the second head mounting member; and an urging member which is arranged on a side opposite to an opposing surface of the first head mounting member and the second head mounting member with respect to the main frame, between the first and second head mounting members and the head-side frame, and which is configured to urge the head-side frame in a direction of separating away from the main frame, wherein a counteraction of a pressing force that acts on the head-side frame from the urging member acts on the first head mounting member and the second head mounting member from the head-side frame.

2. The head unit according to claim 1,

wherein a relationship between the pressing force that acts on the head-side frame from the urging member and a force that acts on the first head mounting member or the second head mounting member from the urging member as the counteraction of the pressing force is completed between the first head mounting member or the second head mounting member and the head-side frame.

3. The head unit according to claim 1,

wherein the head-side frame has a U-shape in sectional view, and includes:

a flat portion extending in the width direction; and a pair of side-surface portions standing from side end edges of the flat portion in a longitudinal direction, and

wherein the urging member is a flat spring having one end portion fixed to the first head mounting member or the second head mounting member and another end portion pressed against an inner side surface of the side-surface portion of the head-side frame on a side opposite to the main frame.

4. The head unit according to claim 3,

further comprising a head fixing spring configured to urge the head-side frame in a direction of approaching the first head mounting member or the second head mounting member,

wherein the flat portion of the head-side frame is held in press-contact with the first head mounting member and the second head mounting member by an urging force of the head fixing spring, and the flat portion slides along a sliding portion of the second head mounting member at the time of angle adjustment of the recording head with the head angle adjustment mechanism, and

wherein a sliding plate having a slidability and a rigidity greater than those of the second head mounting member is arranged on a lower surface of the sliding portion with which the flat portion slides.

5. The head unit according to claim 4,

wherein the head-side frame has a height adjustment screw configured to change a position of the head-side frame in a vertical direction with respect to the second head mounting member by reciprocally moving in a

16

direction of coming closer to or separating away from the first head mounting member or the second head mounting member, and wherein the height adjustment screw is held in press-contact with the second head mounting member via the sliding plate by the head fixing spring.

6. The head unit according to claim 4, wherein the sliding portion has an engagement claw configured to engage with an engaged portion formed on the sliding plate, and the sliding plate is held on the sliding portion through engagement between the engagement claw and the engaged portion under a state in which the head-side frame is removed.

7. The head unit according to claim 3,

wherein the head angle adjustment mechanism includes: a first angle adjustment screw which is provided on an opposing surface of the second head mounting member with respect to the side-surface portion, and is reciprocally movable in a direction of coming closer to or separating away from the side-surface portion; and

a second angle adjustment screw which is provided on an opposing surface of the side-surface portion with respect to the second head mounting member, and is reciprocally movable in a direction of coming closer to or separating away from the second head mounting member,

wherein the first angle adjustment screw and the second angle adjustment screw are configured to reciprocally move on the same axis while maintaining a contact state with an urging force of the urging member.

8. An inkjet recording apparatus comprising the head unit of claim 1.

9. A head unit, comprising:

a recording head including a plurality of nozzles configured to eject ink onto a recording medium; a head-side frame mounted to the recording head; a unit frame configured to hold one or more recording heads on both side surfaces of a main frame having a flat-plate shape and standing along a width direction orthogonal to a conveyance direction of the recording medium;

a first head mounting member which is fixed to the main frame, and includes a support shaft configured to swingably support one end portion of the head-side frame in the width direction;

a second head mounting member which is fixed to the main frame, and is configured to support another end portion of the head-side frame in the width direction;

a head angle adjustment mechanism configured to adjust an angle of the recording head in a horizontal direction with respect to the unit frame by changing a position of the head-side frame in the horizontal direction with respect to the second head mounting member; and an urging member which is arranged on a side opposite to an opposing surface of the first head mounting member and the second head mounting member with respect to the main frame, and is configured to urge the head-side frame in a direction of separating away from the main frame,

wherein a counteraction of a pressing force that acts on the head-side frame from the urging member acts on the first head mounting member and the second head mounting member from the head-side frame,

wherein the head-side frame has a U-shape in sectional view, and includes:

a flat portion extending in the width direction; and

17

a pair of side-surface portions standing from side end edges of the flat portion in a longitudinal direction, and

wherein the urging member is a flat spring having one end portion fixed to the first head mounting member or the second head mounting member and another end portion pressed against an inner side surface of the side-surface portion of the head-side frame on a side opposite to the main frame. 5
